Technical drawing of a mechanical assembly, labeled "Fig. 2." in cursive script. The drawing shows a central vertical structure with various components labeled with numbers. Labels include: 1, 2, 3, 4, 5, 6, 7, 8, 9, 10, 11, 12, 13, 14, 15, 16, 17, 18, 19, 20, 21, 22, 23, 24, 25, 26, 27, 28, 29, 30, and 31. The assembly appears to be a complex gear or linkage system.

UNITED STATES PATENT OFFICE.

FRANCIS HARPER BOYER, OF DE QUINCY, LOUISIANA.

GATE

Application filed September 27, 1924. Serial No. 740,357.

My invention relates to improvements in gates for roadways, and it consists in the combination, constructions, and arrangements herein described and claimed.

5 An object of the invention is to provide a gate construction which is adapted to be placed in a roadway in a desirable place, as, for example, an opening in a fence, at one side of a railway crossing or at like place, 10 and which comprises a pair of vertically swingable normally closed gate members and means adapted to be actuated by the weight of an approaching vehicle or traveler to swing the gate members to open position.

15 A further object of the invention is the provision in a gate construction of the character described of means normally preventing the gate member operating means from functioning to open the gate, the means controlling the operation of the gate member operating means being adapted to be operated by the driver of an approaching vehicle to permit the gate operating means to act to open the gate without there being any necessity of the driver of the vehicle dismounting from the vehicle or bringing the approaching vehicle to a complete stop.

Other objects and advantages will be apparent from the following description considered in conjunction with the accompanying drawings, in which,

Figure 1 is a plan view of a gate construction embodying the invention,

Figure 2 is a longitudinal vertical section through the gate construction,

Figure 3 is a transverse vertical section,

Figure 4 is a plan view of a modified form of gate construction embodying the same invention,

Figure 5 is a section along the line 5—5 of Figure 4,

Figure 6 is a perspective view of a gate bar and its supporting post which are comprised in the modification,

Figure 7 is a perspective view of a link for transmitting motion to the bar which is exhibited in Figure 6, and

Fig. 8 is a fragmentary perspective view showing a pair of coupling members and a portion of a rod for connecting the coupling members to each other, the structure exhibited in Figure 8 being comprised in each of the hereinbefore mentioned forms of the device.

55 A gate construction embodying the invention in the form exhibited in Figures 1, 2,

and 3 comprises a supporting frame adapted to be positioned in a cavity 1 in a roadway 2. The supporting frame comprises a pair of stringers 3 connected and held in parallel relation by end transverse members 4 and transverse member 5 which are located intermediate the end members 4 and the transverse median line of the frame. A platform which is mounted in the said frame includes end sections fixed to the stringers 3 and extending from the transverse members 4 to the transverse members 5 and a pair of vertically swingable inner sections 7 which are secured upon the inner arms of pairs of hinge levers 8. The latter are enlarged downwardly intermediate their ends as indicated at 9, said enlargements being received in transverse slots 10 in the upper sides of the transverse members 5 and are attached to the latter by horizontal pivots 11, whereby the sections 7 of the platform are swingable vertically between the stringers 3. The outer end portions of the hinge levers 8 work in slots 12 in the sections 6 of the platform and are weighed so that the sections 7 normally will be maintained in the plane of the sections 6, and the upper face of the entire platform thus normally will be in the plane of the surface of the roadway 2. The weighted outer end portions of the levers are indicated at 13 and as illustrated to advantage in Figure 2.

The sections 7 of the platform terminate at their inner ends adjacent to each other. 90 Relatively narrow and thin plates 14 are secured upon the outer end portions of the sections 7 of the platform between the slots 12 and overlap the adjacent end portions of the sections 6 so that the vehicle can pass 95 smoothly from one of the sections 6 over the adjacent strip 14 onto the adjacent movable section 7, thence onto the other movable section 7 and across the other strip 14 to the second fixed section 6 of the platform. 100

The inner end portions of the sections 7 are connected by coupling members 15 and 16 respectively, the coupling member 15 being secured to the underside of the inner end portion of one of the sections 7 while 105 the coupling member 16 is secured to the underside of the inner end portion of the other section 7. Each member 15 is provided at its inner end with a pair of spaced ears 17 between which an extending lug 18 110 on the inner end of the associated member 16 is received. Alined slots 19 are formed

through the ears 17 of each member 15 for loosely receiving a rod 20 which extends through a transverse opening in the lug 18. The rod 20 is movable longitudinally of the 5 slots 19 and the inner end portions of the sections 7 thus have limited swinging movement vertically, the rod 20 moving vertically with the inner end portions of the sections 7.

The sections 7 of the platform may swing 10 downwardly from the plane of the section 6 to oppositely inclined positions, and each section 7 will then be supported upon a pair of spaced transverse rest bars 21 and 22 respectively which extend between the stringers 3, the rest bar 22 being located nearer to the transverse median line of the frame than the rest bar 21 and being located at a lower level than the rest bar 21 so that each section 7 will be supported upon both the rest 15 bar 21 and the rest bar 22 when the section 7 is in downwardly inclined position. A rock shaft 23 is journaled adjacent to its opposite ends in aligned openings in the stringers 3 and is located directly underneath the rod 20. A stop block 24 is secured on the rock shaft 23 intermediate the length of the latter and extends above the rock shaft to position to engage with the underside of the rod 20 when the rock shaft 23 is 20 in normal position and to then prevent downward movement of the rod 20 from the position illustrated in Figures 2 and 3, whereby the sections 7 of the platform will be held against swinging downward at their 25 inner ends from the plane of the sections 6 when the member 24 supports the rod 20. The member 24 is provided with a depending extension 25 which is of relatively great weight and which therefore is urged by 30 gravity to position to cause the member 24 to engage with the rod 20. The ends of the rock shaft 23 are bent at right angles to the body of the rock shaft to provide rocker arms 26. Two standards 27 respectively are 35 secured at their lower ends to the stringers 3 at opposite sides of the platform and laterally of opposite ends of the transverse median line of the platform. A lever 28 is pivoted intermediate its ends on the upper 40 end portion of each of the standards 27 to swing about an axis parallel to the axis of the rock shaft 23. Each lever 28 is connected at its inner end by a flexible motion transmitting member 29 to the outer end of 45 the corresponding rocker arm 26. A pull string 30 may extend from the outer end of the levers 28. When the pull string 30 has been grasped and is pulled downward to 50 cause a corresponding movement of the outer end of the lever 28 to which it is attached, the rock shaft 23 will be rocked from normal position and the member 24 will be swung to position to engage with the 55 rod 20. The opposite end portions of the 60 rod 20 extend through vertical slots 31 in

the stringers 3 and are provided adjacent to their outer ends with rollers 32 which are in rolling contact with vertical guideways 33 at the inner ends of the vertical slots 31.

Two posts 34 respectively are secured upon the stringers 3 above the vertical slots 31. Gate members 35 are carried by the inner end portions of levers 36 which are supported intermediate their ends by horizontal pivot elements 37 on the upper end portions of the posts 34. The gate members 35 and the inner end portions 36 of the levers are of greater weight than the outer end portions of the levers, whereby the action of gravity will tend to hold the gate members 35 in the position illustrated in Figures 1, 2, and 3, in which position the gate members provide an obstruction across the platform. The outer end portions of the levers 36 are indicated at 38 and are enlarged vertically outwardly of the horizontal pivot elements 37. These enlarged outer end portions of the levers are provided with oppositely inclined slots 39 which are 45 engaged by loops 40 at the upper ends of links 41 which are attached at their lower ends to the outer end portions of the rod 20, as indicated at 42.

From the foregoing description of the various parts of the device, the operation thereof will be readily understood. A motorist or other traveler approaching the gate members 35 grasps the adjacent pull string 30. A pull on the string 30 will cause rocking of the shaft 23 and movement of the member 24 out of position to engage with the rod 20. Further movement of the motorist or other traveler toward the gate members 35 will cause a weight to be placed on one of the movable platform members 7 and the inner end portions of the members 7 will be swung downwardly until they rest upon the transverse bars 21-22. This downward movement of the platform section wall cause a corresponding movement of the rod 20 and a pull will be caused on the outer end portions of the levers 36 through the links 41. This pull on the outer end portions of the levers 36 will cause the inner end portions of said levers to be swung upwardly and apart so that passage of the motorist or other traveler across the sections 7 of the platform will be unobstructed. As soon as the weight of the motorist or other traveler has been removed from both of the sections 7, these sections will be swung upwardly to the plane of the platform under the action of gravity on the relatively heavy outer end portions of the levers 8-13 and the stop member 24 on the rock shaft 23 also will be permitted to move as a result of the action of gravity to position to engage with the underside of the rod 20 and to prevent downward movement of sections 7 of the platform 130

until the stop member 24 has been moved out of engagement with the rod 20 as a result of rocking of the rock shaft 23 which will not take place until one of the levers 28 is again 5 operated by means of the pull string 30.

In the form of the device illustrated in Figures 4 and 5, two of the supporting frames are provided and are respectively disposed in a roadway at opposite sides of a 10 railway track 50. Like reference characters have been applied to like parts of the two forms of the device and I shall confine my 15 description of the modification which is illustrated in Figures 4 and 5 to a statement of the points of difference between the modifications and the form of the device which has been hereinbefore fully described. Each 20 of the supporting frames of the modified device has a pair of stringers 3' which are similar and identical in essential respects with the stringers 3 of the preferred form of the device and which support a platform which comprises fixed sections 6 and the movable sections 7 as hereinbefore described. The 25 rock shaft 23, the supporting or stop member 24 together with the standards 27, the levers 28 and the connections between levers 28 and the rock shaft 23 are omitted from the modified form of device. The posts 34 30 of the preferred form of the device are replaced by similar posts 34' which carry bars 36'. Each gate bar 36' is pivotally supported intermediate its length on the upper end portion of the corresponding post 34' for 35 swinging movement about a horizontal axis and the inner end portion of each gate bar 36' extends nearly half way across the platform and cooperates with the inner end portion of the opposite gate bar 36' to provide 40 an obstruction across the platform. The outer end portion of each gate bar 36' is indicated at 38' and is provided with a transverse slot 39' for engaging with the loop portion 40' of a link 41' which is connected 45 with the adjacent end of the rod 20 and which differs from the link 41 of the preferred form of the device only in that it is of greater length than the latter. There is no necessity 50 for operating a stop member when the modification is employed and therefore the weight of a traveler approaching the transverse median line of the platform of each supporting structure will cause opening of the gate members. In actual practice, an 55 overhead frame (not shown) would be placed at opposite sides of the track, and probably would carry a signal of any suitable known type of construction to apprise approaching travelers of the presence of the 60 railway track and also would carry a sign which would inform the approaching traveler that he should move forward onto the platform and that the gate would then open.

65 Obviously the invention is susceptible of

embodiments in forms other than those which are illustrated in the accompanying drawings, and I consider as my own all such modifications and adaptations thereof as fairly fall within the scope of the appended 70 claims.

I claim:

1. A gate construction comprising a platform having stationary horizontal end sections and a pair of intermediate sections 75 mounted to swing downwardly at their inner ends from the plane of the stationary sections, gravity means tending to hold said swingable sections of the platform in the plane of the stationary end sections, a pair 80 of coupling members secured to the inner end portions of said swingable platform section, said coupling members having overlapping portions at their inner ends formed with aligned longitudinal slots, a rod extending through said aligned slots transversely of the platform and cooperating with said lapped portions of the coupling members to provide a loose connection between the inner 85 ends of said swingable platform sections, 90 said rod being movable vertically with the inner ends of the swingable sections of the platform, a pair of swingable cooperative gate members supported upon said platform, said gate members being adapted to swing 95 vertically from horizontal position across the platform to substantially vertical position at opposite sides of the platform, weighted members extending beyond the outer ends 100 of said gate members, and links connecting 105 said weighted members with the ends of said rod, whereby downward swinging movement of the inner ends of said swingable platform sections will swing said gate members to vertical position, a rock shaft supported beneath said rod in parallel relation to the latter, a stop member carried by said rock shaft positioned to engage with the rod and to prevent downward movement of said rod, and manually operable means extending 110 above the level of said platform for rocking said rock shaft to swing said stop member out of position to engage said rod.

2. A gate construction comprising a platform having stationary horizontal end sections and a pair of intermediate sections mounted to swing downwardly at their inner ends from the plane of the stationary sections, gravity means tending to hold said swingable sections of the platform in the plane of the stationary end sections, a pair 115 of coupling members secured to the inner end portions of said swingable platform section, said coupling members having overlapped portions at their inner ends, a rod extending through said lapped portions transversely of the platform and cooperating with said lapped portions of the coupling member to provide a loose connection 120 between the inner ends of said swingable plat- 125 130

form sections, said rod being movable vertically with the inner ends of the swingable sections of the platform, a pair of swingable cooperative gate members supported upon said platform, said gate members being adapted to swing vertically from horizontal position across the platform to substantially vertical position at opposite sides of the platform, gravity members extending from the outer ends of said gate members, said last-named gravity members having down-

wardly and outwardly inclined slots formed therein, and links having loop portions at their upper ends slidably engaged with the slotted portions of said gravity members, 15 said links being connected at their lower ends to the ends of said rod, whereby downward swinging movement of the inner ends of said swingable platform sections will swing said gate members to vertical position. 20

FRANCIS HARPER BOYER.
